US0D1017422S

(12) United States Design Patent (10) Patent No.: US D1,017,422 S
(45) Date of Patent: * Mar. 12, 2024

(54) CONTAINER

- (71) Applicant: PepsiCo, Inc., Purchase, NY (US)
- (72) Inventors: Niklas Gustafsson, New York, NY (US); Maria Hanshella R. Magno, Union, NJ (US); Andrew Richard Phinney, Jersey City, NJ (US); Klaus Rosburg, Brooklyn, NY (US); Koby Hebborn Trout, Brooklyn, NY (US); Marc Thomas Wiescinski, Downers Grove, IL (US); Marcos Orlando Ortiz, Tuckahoe, NY (US); Joseph Thomas Gar Jun Smith, Reading (GB); Matthew Stewart Twiss, East Hanney (GB); Daniel K. Patu, Denver, CO (US)
- (73) Assignee: PepsiCo, Inc., Purchase, NY (US)
- () Term: 15 Years
- (21) Appl. No.: 29/885,163
- (22) Filed: Feb. 21, 2023

Related U.S. Application Data

- (63) Continuation of application No. 29/686,511, filed on Apr. 4, 2019, now Pat. No. Des. 980,082.
